UNITED STATES PATENT OFFICE

WILLIAM FAGERGREN, OF SALT LAKE CITY, UTAH, ASSIGNOR TO UNIVERSAL ENGINEERING COMPANY, OF SALT LAKE CITY, UTAH, A CORPORATION OF UTAH

APPARATUS FOR CIRCULATING AND DISTRIBUTING FLOTATION PULP

Application filed November 9, 1927. Serial No. 232,164.

This invention relates to an apparatus for circulating and distributing pulp in the practice of the flotation process, and its principal objects are:

5 First. To provide means for efficiently subjecting flotation pulp again and again to the action of the impeller in the barrel-type of flotation machines, and more particularly in the flotation machines forming the subjects 10 of the U. S. Patent No. 1,361,342 granted to Irving R. Margetts and myself, and my pending application for patent, filed November 9, 1927, Serial No. 232,165.

Second. To prevent the pulp from "short 15 circuiting" in passing through the flotation machine.

Third. To efficiently circulate the pulp through an individual machine and to selectively distribute the same for further treatment 20 successively through other individual machines.

In the practice of the flotation process for extracting the values from metalliferous ores, it is usually advantageous to effect the treatment 25 in stages, these stages being carried out in different machines. That is to say, the pulp is passed through the first machine and a certain proportion of the values extracted; the tailings from this machine are then passed 30 through a second machine, the tailings from the second through a third, and so on, until substantially the maximum attainable separation has been reached. A clean separation 35 of the mineral from its gangue can seldom or never be attained in one machine or in one stage.

By means of the present invention, the pulp is circulated through each machine and subjected to aeration again and again before it is 40 allowed to pass on to the next machine. This thorough aeration is accomplished by feeding or projecting the pulp into each machine, substantially at right angles to the elements of the impeller and preferably tangent to its 45 periphery. Thus, the feed strikes the impeller transversely, so that it is carried round and round before reaching the opposite end of the impeller. By having the inlet to the machine near one end of the impeller, and 50 maintaining a constant feed, the pulp will

be forced gradually along the longitudinal dimension of the impeller, and theoretically, will travel in a path having substantially the form of a helix. The pitch of the helix is determined by the relation of the amount of 55 feed to the speed of rotation of the impeller. In general, the smaller the feed for a certain speed of rotation of the impeller, the smaller will be the pitch, and the greater the feed, the greater will be the pitch. Thus, by regulating 60 the circulation of the pulp in this machine, a high degree of extraction is obtained.

The tailings outlet of the machine is located in the end of the housing and above the impeller, compelling the pulp to take a circuitous 65 path from the pulp inlet to the tailings outlet, so that while the pulp is in transit, the bubbled aeration has the fullest opportunity of picking up the values and carrying them off 70 at the top of the machine.

By grouping the flotation machines, and arranging the individual machines so that the tailings from any machine can be carried to any of the successive machines, it is possible to achieve a combination capable of extracting 75 to a maximum degree, the values of any ore, no matter how complex.

The features of this invention for which the protection of Letters Patent is desired, are collectively grouped in the claims concluding 80 this specification.

In the drawings, which illustrate merely one embodiment of this invention,

Fig. 1 represents a longitudinal section through a group of barrel-type flotation machines equipped with this invention, the section being taken in the plane indicated by line 1—1 in Fig. 3;

Fig. 2, a section on line 2—2, Fig. 1, enlarged;

Fig. 3, a section on line 3—3, Fig. 1;

Fig. 4, a section on line 4—4, Fig. 3, reflected from a mirror plane;

Fig. 5, a group of machines in diagrammatic perspective; and,

Fig. 6, a similar group with a modification.

Referring to the drawings, 20 represents an impeller rigidly mounted on a substantially horizontal shaft 25 which may be journaled in bearings 24. The impeller has its 100

motion in the agitation chamber 26 which is defined by the walls of the housing. At 39 is a shield which extends lengthwise of the impeller just above its peripheral elements 35, and from end to end of the housing. One edge of the shield is spaced apart from the wall 21 by only a very small amount, possibly $\frac{3}{8}$ of an inch. The other or cutting edge, of the shield, is spaced apart from the opposite wall a much greater distance, though still restricted, as indicated at 41. At 46 is an adjustable baffle or valve movably supported, for instance on pivots, whose common axis extends lengthwise of the baffle, and located 10 contiguous or in proximity to the said opposite wall, by means of which the rate of circulation, and the amount of pulp operated upon, may be controlled. In effecting this control, the baffle, which naturally has a pivoted or pivotal edge and a free edge, will have the free edge movable towards or away from the shield and its cutting edge. The baffle may be actuated by a suitable mechanism, such for instance, as the rod and hand wheel 15 shown in the present drawing, and fully described in application 232,165. By means of the actuating mechanism, the free edge of the baffle may be seated substantially in contact with the shield adjacent its cutting edge. 20

25 The pulp enters the chamber 26 through the opening 27 which is preferably inclined downwardly so as to conduct the incoming stream of pulp preferably tangent to the impeller. When the impeller is rotated, circular motion is imparted to the pulp, which then follows approximately the path indicated by the arrows. The pulp is drawn around the impeller repeatedly, following virtually a helical course, as indicated in 30 Figs. 5 and 6, until finally it follows the arrow 28 and flows out of the agitation chamber through the outlet 59. The theoretical pitch of the helices may be calculated from the quantity of the feed and the speed of rotation. 35 The outlet 59 opens into the part 29-1 of launder 29, where it may encounter the variable weir 30 and flow over into the part 29-2 of the launder. From here, when the regulating gate 40-1 is closed, the tailings from the first machine flow down through the conductors 31-1 and 32-1 as well as through the various connecting fittings, through the opening 27-1 into the agitating chamber 26-1 of the second machine. 40 Here the tailings go through an agitating and aerating cycle similar to the one previously described.

Subsequently the tailings from the second machine go to the third, and so on from machine to machine.

In Fig. 5, the course traveled by the pulp can be seen at a glance. The heavy lines indicate diagrammatically the course, while the lines 20, 20-1, 20-2, and so on indicate the impellers around which the course leads.

If desired, the course may be made to omit any machine by simply placing stoppers or plugs (not shown) in the intakes such as 31, and in the outlets, such as 59, of the particular machine or machines not wanted in the course. At the same time the corresponding gate 40 and corresponding weir 30 in the launder should be removed. In Fig. 6, the second machine is indicated at cut out of the course.

The initial pulp begins its course at 34, the tailings from one machine becoming the feed or fractional pulp for a succeeding machine or machines.

The novelty of the present invention consists in providing means for compelling the liquid or semi-liquid under treatment, to follow a circuitous, substantially regulable helical course from the inlet to the outlet of individual flotation machines of the barrel type, and from one machine to another in a plurality of machines arranged in series or batteries, for the fractional, progressive treatment of the material operated upon.

The travel of the incoming stream of pulp transverse and substantially tangent to the impeller, compels the pulp to follow the influence of the impeller and thus to be drawn round and round as described, and prevents the pulp short circuiting from the pulp inlet to the tailings outlet. By "short circuiting" I mean, to travel in a substantially direct path from the inlet to the outlet. This advantage will become more manifest by referring to Patent No. 1,361,342 previously mentioned herein, where the inlet to the machine directs the stream of incoming pulp longitudinally along the peripheral elements of the impeller. For this reason, a considerable percentage of the pulp reaches the tailings outlet in too direct a manner, and so the pulp is not subjected to as thorough an aeration as in the present apparatus.

The present drawings show the flotation machine described in my co-pending application for patent, Serial Number 232,165, also previously mentioned herein, incorporated with the present apparatus.

I do not assert that the initial stream of pulp entering the present apparatus retains its identity as regards the individual particles of matter making up the helical stream at any particular moment, but rather, that every particle is compelled to follow approximately the helical course outlined.

While a specific embodiment of this invention is herein shown and described, it is to be clearly understood that all the detailed parts thereof, may or may not be shown in the preferred forms, and further, that the preferred forms may be varied from time to time, as the development of this invention and the arts to which it appertains, advance. Therefore, that which forms an essential and characteristic part of this invention, will

be readily discernible from the claims in which its spirit is generalized.

Having fully described my invention, what I claim is:

5 1. An apparatus for circulating flotation pulp comprising a rotatable barrel-type impeller, a housing for said impeller, a shield over said impeller, said shield having a cutting edge spaced apart from a wall of said housing, a baffle pivoted lengthwise along one edge thereof so the free baffle edge shall be movable towards or away from said cutting edge, an inlet for pulp directed substantially tangential and at right angles to the peripheral elements of the said impeller, and an outlet for tailings above said impeller.

10 2. An apparatus for circulating flotation pulp comprising a rotatable barrel-type impeller, a housing for said impeller, a shield over said impeller, said shield having a cutting edge spaced apart from a wall of said housing, a baffle pivoted lengthwise along one edge thereof so the free baffle edge shall be movable towards or away from said cutting edge, an inlet for pulp directed substantially at right angles to and below the peripheral elements of the said impeller, and an outlet for tailings above said impeller.

15 3. An apparatus for circulating and distributing flotation pulp comprising a plurality of barrel-type flotation machines spaced apart from each other transverse to the axes of the impellers thereof, a shield over each impeller, said shields having cutting edges, baffles pivoted lengthwise of and in proximity to said cutting edges, the free edges of said baffles movable towards and away from said cutting edges, feed inlets directed substantially tangential to, and at right angles to the peripheral elements of, the impellers, tailings outlets above the said impellers, and means for conducting liquid from each tailings outlet to any subsequent feed inlet.

20 4. An apparatus for circulating and distributing flotation pulp comprising a rotatable barrel-type impeller placed substantially horizontal, a housing defining an agitation chamber around said impeller, a restricted space defined longitudinally between said housing and said impeller, a shield over said impeller, said shield having a cutting edge, a baffle pivoted along one edge thereof in proximity to said cutting edge and above said restricted space, the free edge of said baffle movable towards said cutting edge, an inlet for pulp located on the other side of said restricted space with reference to said baffle, the said inlet being directed at substantially right angles to the peripheral elements of said impeller; and an outlet for tailings on the other side, and near the other end, of said impeller.

25 5. An apparatus for circulating and distributing flotation pulp, comprising a plu-

rality of flotation machines having barrel-type impellers spaced apart from one another transverse to the axes of the impellers, shields having cutting edges over said impellers, baffles pivoted lengthwise of and in proximity to said cutting edges, the free edges of said baffles movable towards said cutting edges, a launder extending in the said transverse direction, feed inlets directed to points below said impellers substantially at right angles to the peripheral elements of the impellers, conductors extending from said launders to said inlets, said conductors located in the space between successive machines after the first, and outlets leading from points above said impellers into said launders.

70 6. A rotatable impeller having staves of circular cross-section spaced apart circumferentially around the said impeller, a shield over said impeller, a cutting edge on said shield, a pivoted baffle in operative proximity to said cutting edge, a pulp inlet below said shield, said pulp inlet being directed substantially at right angles to said staves and substantially tangent to the exterior circumference of said impeller, and an outlet for tailings above said shield.

75 7. A rotatable impeller having staves of circular cross-section spaced apart circumferentially around the said impeller, a shield having a longitudinal cutting edge over said impeller and slightly spaced apart therefrom, said shield following substantially the curvature of the impeller, a housing having a wall spaced apart from the said longitudinal cutting edge, a baffle having a pivotal edge contiguous to said wall and a free edge movable to substantially contact said shield adjacent said cutting edge, a pipe directing a stream of pulp into said housing, said pipe being positioned in proximity to one end of said housing, said stream being transverse to said staves and substantially tangent to the circumference of said impeller, said stream being further, below the horizontal axial plane of said impeller; and an outlet for tailings, said outlet being located above said shield and at the other end of the said housing.

80 8. In testimony whereof, I sign my name hereto.

WILLIAM FAGERGREN.
